UNITED STATES PATENT OFFICE.

THOMAS BLACKWOOD MURRAY, OF SCOTSTOWN, SCOTLAND.

CYLINDER OF COMBUSTION-ENGINES.

1,393,636.

Specification of Letters Patent.

Patented Oct. 11, 1921.

Application filed October 31, 1918. Serial No. 260,526.

To all whom it may concern:

Be it known that I, THOMAS BLACKWOOD MURRAY, a subject of the King of Great Britain and Ireland, and a resident of 5 Scotstown, in the county of Renfrew, Scotland, have invented certain new and useful Improvements in the Cylinders of Combustion-Engines, and of which the following is the specification.

10 The invention relates to combustion engines of the type mainly used for vehicle propulsion and marine purposes, and has for its object an improved construction in which the cylinder head is detachable and 15 in which a compact and easily molded combustion space is provided, the valves are arranged in a simple manner in the head, a minimum perimeter and a minimum area exposed to explosion pressure between cylinder and head obtained, and a very simple 20 form of main cylinder body casting results. The improvements are more particularly applicable to an engine in which the cylinders are cast *en bloc* or in *en bloc* groups.

25 In an engine made according to the invention, the combustion space arranged in the detachable cylinder head is of conoidal or ungulate form. The inlet and exhaust valves are arranged side-by-side at one side 30 of the combustion space, and are of such area and are placed with their axes at such an inclination to the cylinder axis that they may be withdrawn diagonally inward through the detached cylinder head. Thus 35 cages or blocks for them are unnecessary unless desired for some other reason. Furthermore, the area of the valves, the angle of their preferably parallel axes and their position—that is, their distance from the 40 axis of the cylinder—is such that the combustion space is not pocketed to any extent to receive them—rather, they may be said to be received upon the base of a hollow doubly ungular space.

45 An example of the carrying out of the invention in the case of a four cylinder engine in which the cylinders are cast *en bloc* is shown in four accompanying sheets of explanatory drawings, Figure 1, Sheet 1, 50 whereof is a sectional plan to the left and an inverted plan to the right, Figs. 2 and 3, Sheets 2 and 3, sectional side elevations on two planes, and Fig. 4, Sheet 4, a sectional end elevation.

55 As will be seen, the combustion spaces A

in the detachable cylinder head are of ungulate form, the contour of two in plan being clearly visible at the right hand side of Fig. 1, which also shows the very effective jointing area provided. The inlet and exhaust valves B, C, are arranged side-by-side at one side of the combustion space, and are of such area and are placed with their axes at such an inclination to the cylinder axis that they may be withdrawn diagonally inward through the detached head. The passages D from the exhaust valves C pass substantially through the top of the head and at right angles to the valves. The inlet valve passages E communicate with a manifold channel G formed in the upper part of the cylinder casting and closed by the head casting. The sparking plug apertures H are formed diametrically opposite the valves and thus may be well jacketed. A lateral pocket J is formed in the cylinder casting to receive valve mechanism, and this corresponds and makes joint with a similar lateral pocket K in the detachable head. On the top of this latter is a door L giving access to the valves and their parts.

What I claim is:

1. In an internal combustion engine, an engine cylinder and a detachable head therefore recessed on its inner face to afford a combustion space of the conoidal or ungulate form described, in combination with inlet and exhaust valves arranged in the side wall of said recess forming the combustion space, and with their axes so inclined that they may be withdrawn through said space in the cylinder head when the latter is detached together with a valve-operating means arranged at the side of the cylinder in the main cylinder casing and below said removable head to permit the ready detachment of the latter.

2. In an internal combustion engine, an engine cylinder and a detachable head therefore recessed on its inner face to afford a combustion space of the conoidal or ungulate form described, in combination with inlet and exhaust valves arranged side by side in the side wall of said recess forming the combustion space, and with their axes in the same plane with relation to the cylinder axis and so inclined that they may be withdrawn through said space in the cylinder head when the latter is detached together with a valve-operating means arranged at

the side of the cylinder in the main cylinder casing and below said removable head to permit the ready detachment of the latter.

3. An engine of the construction recited in claim 1, having in combination therewith an exhaust passage extending substantially through the top of the head and an inlet passage in the head for connection with a lateral inlet manifold.

10 4. In an internal combustion engine, an engine cylinder and a detachable head therefore recessed on its inner face to afford a combustion space of the conoidal or ungulate form described, having oppositely inclined 15 side walls, one of said walls being apertured to afford inlet and outlet ports for the com-

bustion chamber, and the opposed side wall being apertured to receive an ignition device, the relative inclination and arrangement of said walls with relation to each other and to the cylinder being such as to permit the inward withdrawal of the valves through said combustion space when the cylinder head is detached together with valve operating means supported on a portion of the engine casing independent of said removable head to permit of ready detachment of the latter. 20 25

In testimony whereof I have signed my name to this specification.

THOMAS BLACKWOOD MURRAY.
